UNITED STATES PATENT OFFICE.

FRITZ MÖBIUS, OF GROSS-KOLZIG, GERMANY, ASSIGNOR TO CHARLES FREDERICK RALPH GIESLER, OF LONDON, ENGLAND.

MACHINE FOR THE PRODUCTION OF HORSEHAIR THREADS.

Application filed June 16, 1923. Serial No. 645,755.

To all whom it may concern:

Be it known that I, FRITZ MÖBIUS, a citizen of Germany, residing at Gross-Kolzig, in the Province of Brandenburg, Germany, have invented certain new and useful improvements in Machines for the Production of Horsehair Threads, of which the following is a specification.

This invention relates to an improvement in machines for the production of endless horsehair threads and more specially to the feeding device. The feeding device consists of a finger serving as abutment for the horsehair coming from the reservoir, a needle opposite said finger, a pair of feeding cylinders and a bow designed to insert the horsehair between the feeding cylinders. The finger serves as abutment for the needle and for the horsehair and bears from the rear against the bundle of horsehair. The needle is moved from the front towards the bundle of horsehair and the finger to grip one or several hairs of the bundle, whereupon the needle and finger move downward to pull the hairs out of the bundle and conduct them to the feeding cylinders. When the finger and the needle have moved down to between the conical heads of the cylinders they move away from one another to release the horsehair pulled out of the bundle. This horsehair enters at first between the conical heads of the cylinders and is then drawn between said cylinders by means of the inserting bow, the horsehair being thus gripped by the cylinders and fed to the spinning machine, that is to say to the spindle of same.

The invention will be best understood from a consideration of the following detailed description taken in connection with the accompanying drawings forming a part of this specification, with the understanding that while on the drawings one embodiment of the invention is disclosed, the invention is not confined to any strict conformity with the showing of the drawings, but may be embodied in any manner which does not make a material departure from the salient features of the invention.

50 In the drawing:

Fig. 1 shows the machine in side elevation in the position when the needle is gripping one or several horsehairs and pressing the same against the finger.

Fig. 2 shows the feeding device in plan view.

Fig. 3 is a similar view to Fig. 1 showing the several parts in the position when the finger and needle are inserting the pulled out horsehair between the conical heads of the gripper cylinders.

Fig. 4 shows the different parts in the position when the needle and the finger have moved away from the feeding cylinders and the inserting bow is conducting the horsehair between the feeding cylinders by which it is gripped and conveyed through a funnel to the spinning machine.

The operating parts of this feeding device are the finger 1 which serves as an abutment or support for the threads to be pulled out of the bundle 2 of horsehair; the needle 3 which moves towards said finger and descends together with the same thereby pulling one or several threads out of the bundle 2 of horsehair and bringing the same to the gripper cylinders 4, 5; the said gripper cylinders 4, 5 and the inserting bow 6. These parts operate in the following manner:

The finger 1 is adjustably arranged at one end of a lever 7 pivotally mounted on a pivot pin 8. The rearward extension of the lever 7 is acted upon by a cam disc 10 rotated in the direction of arrow 12 from a driving shaft 11. The pivot pin 8 of lever 7 is mounted in a sliding block 13 adapted to execute a reciprocating movement between the straight guides 14. The movement of the sliding block is controlled by means of a rod 15 pivoted on a crank arm 16 carried by the driving shaft 11. The sliding block 13 carries further a two armed lever 17, 18 in the arm 17 on which the needle 3 is mounted, the other arm 18 of said lever being acted upon by the cam shaped end 19 of the crank arm 16 designed to oscillate said two armed lever 17, 18. A spring 20 attached on the one hand to rod 15 and on the other hand to the arm 18 of the lever serves to hold said lever against the cam 19. From the chain wheel 21 of driving shaft 11 another chain wheel 23 is rotated by means of a chain 22, said second chain wheel 23 rotating through the intermediary of a bevel wheel 24, a small bevel wheel 25 keyed on the end of the gripper cylinder 4. The other gripper cyl-

inder 5, opposite gripper cylinder 4 is mounted on an arm 26 which is pivotally mounted on a pin 27 on the frame 28 and pressed by the action of spring 29 to hold the cylinder 5 against the gripper cylinder 4. The gripper cylinders are grooved on their circumference, so that they grip at their rotation the horsehair threads fed to them and convey them through the funnel 30 to the spinning machine. The gripper cylinders 4 and 5 have conical pointed heads 31 so that the horsehair threads pulled out of bundle 2 may be inserted between the gripper cylinders by means of the feeding bow 6. The feeding bow 6 consists of a wire loop (Fig. 2) pivotally mounted at the end of lever 7. A movable arm 32 of this feeding bow 6 slides upon a rail 33 which determines the position of the feeding bow 6 with regard to the gripper cylinders 4, 5.

The bundle 2 of horsehair projects from a box 34 conveniently fixed on the frame 35 of the machine.

25 The operation of the feeding device is as follows:

On rotation of the driving shaft 11 in the direction of the arrow 12 the cams 10 and 19 are moved to permit the finger 1 to be pressed from behind against the bundle 2 of horsehair and the needle 3 to descend towards the finger 1 so that they grip between them one or several horsehair threads (Fig. 1).

35 The crank 16 next causes the advance of the sliding block 13 between the straight guides 14, the needle 3 remaining in contact with the finger 1. The horsehair threads clamped between the finger 1 and the needle 3 are thus pulled out of the bundle 2 and conveyed towards the gripper cylinders 4, 5, the sliding block 13 moving in such a manner that the finger 1 and the needle are brought between the conical heads 31 of the gripper cylinders 4 and 5 (Fig. 3).

With the forward movement of the sliding block 13 the feeding bow 6 is also moved forward above the gripper cylinders 4, 5, so that the horsehair threads, which have been pulled out of the bundle by the needle, and brought to the gripper cylinders are situated in the feeding bow 6 between the conical heads 31 of said gripper cylinders.

55 The arm 18 of lever 17, 18 is then pushed back by the action of cam 19 (Fig. 4) and the needle 3 is raised from the finger 1, whereby the horsehair threads are released.

The sliding block 13 is then pulled back between the straight guides 14 through the action of crank 16, whereby the finger and the needle are both pulled back, the two parts being however no longer in engagement. The feeding bow 6 is simultaneously drawn

65 back and catches the released horsehair

drawing the descending ends of the same between the conical heads 31 of the gripper cylinders 4 and 5 and finally between the gripper cylinders (Fig. 4).

As the gripper cylinders rotate in opposite directions they grip the horsehair and convey the same to the feeding funnel 30 and consequently to the spinning device where they are spun in the usual manner together with the feeding thread and the winding threads.

This feeding device works in a very simple and reliable manner as the horsehair threads are clamped between the finger 1 and the needle 3, these two tools being simultaneously moved in such a manner that the pulled out horsehair threads are inserted between the conical heads of the gripper cylinders, whereupon the feeding bow brings the horsehair threads securely between the heads 31 of the cylinders 4, 5, so that they are securely gripped by the said cylinders. The number of horsehair threads gripped by the needle depends on the width or thickness of the point of the needle.

I claim:

1. A feeding mechanism for machines for the production of endless horsehair threads comprising in combination a reservoir for the horsehair open at the lower end from which the bundle of horsehair projects, a finger, a needle, designed to grip some of the said horsehair threads against said finger, means for moving said needle towards and away from said finger, means for lowering said needle and finger simultaneously, a feeding bow designed to receive the horsehair threads released by said needle when the same is moved away from the finger, two gripper cylinders below said feeding bow, means for moving said feeding bow with regard to said gripper cylinders to feed the horsehair threads between said cylinders, and means for rotating said gripper cylinders in opposite directions to convey the horsehair threads towards a spinning mechanism.

2. A feeding mechanism for machines for the production of endless horsehair threads comprising in combination a reservoir for the horsehair open at the lower end from which the bundle of horsehair projects, a finger adapted to be moved into contact with said bundle of horsehair, a needle designed to grip some of the said horsehair threads against said finger, means for moving said finger towards and away from said finger, a sliding block, straight guides for said sliding block and a lever mechanism for lowering said needle and finger simultaneously, a feeding bow designed to receive the horsehair threads released by said needle when the same is moved away from the finger, two gripper cylinders below said feeding bow, means for moving said feeding bow with re-

gard to said gripper cylinders to feed the horsehair threads between said cylinders, and means for rotating said gripper cylinders in opposite directions to convey the 5 horsehair threads towards a spinning mechanism.

3. A feeding mechanism for machines for the production of endless horsehair threads comprising in combination a reservoir for 10 the horsehair open at the lower end from which the bundle of horsehair projects, a finger adapted to be moved into contact with said bundle of horsehair, a needle designed to grip some of said horsehair threads 15 against said finger, means for moving said needle towards and away from said finger, means for lowering said needle and finger simultaneously, a feeding bow designed to receive the horsehair threads released by

said needle when the same is moved away 20 from the finger, two gripper cylinders below said feeding bow, conical heads of said gripper cylinders forming a space for the reception of the horsehair threads lowered by said needle and finger, means for moving 25 said feeding bow with regard to said gripper cylinders to feed the horsehair threads between said cylinders, and means for rotating said gripper cylinders in opposite directions to convey the horsehair 30 threads towards a spinning mechanism.

In testimony whereof, I have signed my name to this specification at Berlin this 29th day of May, 1923.

FRITZ MÖBIUS.
